RESPIRATOR

Howard B. Lewis, Los Angeles, Calif.

Application November 23, 1936, Serial No. 112,234

15 Claims. (Cl. 128—146)

My invention relates to respirators and particularly to the type of respirator adapted for purifying smoke-charged or dust-laden air to prevent these or other deleterious impurities in the 5 air from being breathed by the wearer.

It is a general object of the invention to provide such a respirator which is constantly ready for use without preliminary adjustment, is efficient, light in weight, and comfortable for the wearer.

Another object resides in the provision of a 10 respirator including a rigid mask adapted to extend around the mouth and nostrils of the wearer, and having a nostril covering portion conforming substantially to the shape of the lower portion 15 of the nose and extending only slightly beyond the nose so that normal vision is not obstructed and so that the wearer may wear glasses or protective goggles without interference.

It is another object of the invention to provide 20 a respirator embodying the mask above described and which includes a face mold attached to the mask and formed of compressible material, such as sponge rubber, or the like, the face mold providing a face-engaging surface conforming substantially to the facial contour of the wearer and the material of the mold being deformable normal to the face-engaging surface so that an air-excluding seal is formed between the wearer's 25 face and the face-engaging surface when the mold is pressed against the face.

It is a further object of the invention to provide 30 in a respirator a rigid mask and a face mold readily attachable to and detachable therefrom. More specifically, it is one of my objects to provide 35 a mask having a rim extending around the mouth and nostrils of the wearer, there being a pair of forwardly projecting hook portions on the rim adjacent the nose covering portion thereof; and a face mold formed of sponge rubber, or the like, having a groove for receiving the rim of the mask and having pockets formed in the groove 40 for engaging the hook portions to retain the face mold on the rim in air-excluding relation therewith.

It is a further object to form the face mold, 45 mentioned in the above paragraph, in the shape of a substantially flat continuous ring having the contoured face-engaging surface formed on one side thereof and having the groove formed in the 50 inner peripheral edge thereof so that when the mold is mounted on the rim of the mask, the mold will be distended to assume the general contour of the rim.

It is another object to provide a respirator 55 which includes a mask having an air inlet open-

ing and a filtering means covering the opening and comprising a shell having perforations in at least three sides thereof, a filtering means in the shell, and a filter spreading member adapted to hold the filtering material in a position exposing 5 a greater area thereof to direct contact with the air entering the perforations than the combined area of the perforations.

It is a still further object of the invention to provide in a respirator a filtering means covering 10 the air inlet and comprising a perforated cover, a sheet of filtering material and an inner filter spreading member formed so as to hold the sheet in a position exposing four spaced faces 15 thereof to direct contact with air entering the perforations, each of the faces having an area substantially equal to the greatest cross-sectional area of the cover.

Another object resides in the provision of a 20 respirator, as described in the above paragraph, in which the cover and the filter spreader are provided with opposed surfaces adapted to grip the entire marginal area of the filter sheet in sealing engagement therewith.

It is another object to provide deformable hook 25 portions on the rim of the mask so that they may be bent laterally, permitting the nose covering portion of the face mold to be made narrower or wider to adapt this portion of the mold to different facial contours of various wearers.

It is another object to provide a respirator of 30 the character described above having an outlet valve comprising a flexible valve plate secured to the outer surface of the mask and covering an outlet opening of the mask, the valve plate being 35 adapted for outward movement relative to the mask to uncover the opening; and a guard strip detachably secured to the mask and covering the valve plate in spaced relation therewith.

These and other objects of the invention, as 40 well as numerous important features of construction, which combine to make an efficient, cheaply constructed respirator of the type specified, will be made clear in the following part of the specification taken in connection with the accompanying 45 drawings and the appended claims.

In the drawings:

Fig. 1 is an elevational perspective view of the 50 respirator embodying the features of my invention.

Fig. 2 is a side elevation of the respirator with a portion broken away to illustrate a feature of the invention.

Fig. 3 is a vertical section through the respirator taken as indicated by the line 3—3 of Fig. 4.

Fig. 4 is a front elevation with a portion of the filtering means broken away to substantially a medial plane.

Fig. 5 is a top plan view of the respirator.

Fig. 6 is a horizontal section through the novel filtering means of the invention taken as indicated by the line 6—6 of Fig. 4.

Fig. 7 is a perspective view of the filter spreading member of the invention, there being portions of this figure broken away to more clearly illustrate certain features of the construction thereof.

My novel respirator, generally designated in the drawings by the numeral 11, includes a rigid mask 12 adapted to cover the nostrils and mouth 15 of a wearer; a face mold 13 secured to the mask and adapted for air-excluding contact with the face of the wearer; an air filtering means 14; and a valved air outlet 15.

The mask 12 is formed of a rigid material, preferably metal, and is shaped to provide a rim 20 conforming generally to the contour of the wearer's face and adapted to cover the mouth and nostrils. The body of the mask 12 is shaped to provide a nose covering portion 21, conforming substantially to the contour of the lower portion of the wearer's nose and extending only slightly forward of the nose; and a mouth covering portion 22 conforming generally to the shape of the mouth and chin, as best shown in Fig. 3. Formed on the rim 20 adjacent the nose covering portion 21 and disposed on opposite sides thereof are two forwardly projecting hook portions 23. The hook portions are preferably provided to be laterally deformable, for a purpose to be explained later. The edge of the rim 20 is preferably flared outwardly, as indicated at 24 in Figs. 2 and 3, for a purpose which will hereinafter be described.

For economy in manufacture, the face mold 13 is preferably molded in the form of a flat continuous ring of sponge rubber and is provided with a groove 25 formed in the inner peripheral edge 26 thereof for receiving the rim 20. The groove extends entirely around the lower portion of the mold and terminates in pockets 27 into which the forwardly projecting hook portions 23 extend, as best shown in Fig. 2; the engagement of the hook portions in the pockets, the resiliency of the rubber and the outwardly flared edges 24 of the rim 20 serving to retain the face mold 13 on the rim in air-excluding relation therewith. The forward portion 28 of the face mold extending between the pockets 27 forming the end of the groove 25 is adapted to be stretched around the flared rim of the nose covering portion, substantially as shown. The face mold 13 is preferably formed with a bead on the outer edge 29, the bead extending entirely around the rim 24 for the purpose of increasing the tensional strength thereof. Likewise, it is preferable to provide an inner bead 30 extending substantially the entire length of the groove 25, as shown. The inner face-engaging surface 31 is preferably formed to substantially conform to the facial contour of the wearer after it is mounted on the rim 20. This

may be best accomplished by increasing the thickness of the mold 13 in certain portions and decreasing the thickness thereof in other portions. As best shown in Fig. 5, the wall thickness of the mold 13 is increased, as indicated at 32 and 33, to provide inwardly projecting portions adapted to substantially conform to the hollows on each side of the wearer's nose. The wall thickness of the mold is decreased, as shown at 34, to provide a comparatively thin, more flexible portion 75 adapted to extend across the bridge of the

wearer's nose and to conform substantially to the contour thereof. Other suitable thickened portions or thinned portions may be provided, as desired, to adapt the face mold to a more perfect fit with the wearer's face.

A head strap 40 having suitable adjustment means 41 is secured to the mask 12 as by suitable snap buttons 42 so as to extend around the wearer's head and hold the respirator in place.

The filtering means 14 is novel in construction and function and includes a cap 45 for securing the filtering means to the mask 12, a cover 46, filtering means 47, and an inner filter spreading means or form 48. The cap 45 is preferably rectangular in shape and provides upwardly sloping end walls 50 and upwardly sloping side walls 51 terminating in an upper flat wall 52 in which is provided a pair of openings 53 having upwardly extending flanges 54 adapted to extend through openings 55 formed in the bottom wall 56 of the mask 12, the upper peripheral portions of the flanges 54 being swaged over the peripheral edge of the openings 55 securing the cap 45 to the mask 12 in air-excluding relation therewith.

The cap 45 serves to rigidly support the filter spreading member 48. Any suitable means such as soldering, welding, or the like, may be employed to secure the filter spreading member 48 to the cap 45 but one preferred manner for accomplishing this purpose is indicated in the drawings with particular reference to Figs. 3, 4, 6, and 7. The filter spreading member 48 includes a rectangular upper frame 60 having a pair of relatively spaced legs 61 and 62 extending downwardly therefrom. The upper frame 60 preferably is provided with a downwardly extending marginal flange 63, the portion of the flange extending across the ends of the frame 60 being increased in width, as shown at 64 in Figs. 4 and 7, for a purpose which will be described later.

In order to secure the member 48 to the cap 45, a downwardly extending marginal flange 65 is provided to extend entirely around the four sides of the cap 45. The frame 60 is inserted within the marginal flange 65 of the cap 45 and the lower edge of the flange 65 is rolled along the sides of the cap 45 to extend under and around the flange 64 substantially as shown in Fig. 3. The portion of the marginal flange 65 extending across the ends of the cap 45 are not rolled around the flange 64 but are bent inwardly to provide an inwardly extending ledge 66 at each end of the cap, as shown in Fig. 4.

The legs 61 and 62 extend longitudinally of the frame 48 and terminate short of the flange 64 extending across the end of the frame so that these portions of the flange overhang the ends of the legs 61 and 62, in the manner shown in Fig. 4, to provide a space 67 between these portions of the flange and the ends of the legs 61 and 62. Likewise, the outer side walls 68 and 69 of the legs 61 and 62 are spaced inwardly from the rolled side edges of the flange 65 to provide a space 70 therebetween as shown in Fig. 3.

The frame 60 and the legs 61 and 62 are preferably formed by stamping from light sheet metal. As shown in Figs. 3 and 7, the legs are formed by drawing the metal so that the walls thereof are substantially W-shaped in cross section, the lower edges of the legs being rounded, as at 71 and 72, and the wall forming the intersection of the legs 61 and 62 being arcuated, as at 73. Cut in the outer walls 68 and 69 of each of the legs 61 and 62 are openings 75 and 76. 75

The openings 75 and 76 extend from a point closely adjacent the ends of the legs 61 and 62 to a point adjacent to and equally spaced from the center of the legs 61 and 62 to provide a center portion 77, the outer portions 78 and 79 thereof being bent inwardly, as shown in Figs. 6 and 7, to provide a center ridge dividing the openings 75 and 76 and extending from the bottom 80 to the top 81 thereof. The inner walls 82 and 83 of the legs 61 and 62 are entirely cut away to provide an opening extending from a point even with the outer end of the opening 75 to a point even with the outer end of the opening 76, substantially as shown in Figs. 6 and 7. The end portions of the outer walls 68 and 69 and the inner walls 82 and 83 form continuous W-shaped surfaces 85 and 86 at opposite ends of the legs 61 and 62 for a purpose which will be herein-after described.

The cover 46 comprises a rectangular box-like shell having side walls 90, end walls 91, a bottom wall 92, and an open top, as indicated at 93 in Figs. 3 and 4. Secured to the opposite end walls 91 are suitable resilient latch members 94 having engager portions 95 adapted to engage the inwardly extended ledges 66 formed on the cap 45 when the open top of the cover is inserted between the rolled side edges of the flange 65, as indicated in Figs. 3 and 4. The side walls 90 of the shell are tapered downwardly at a lesser angle than the taper of the outer walls 68 and 69 of the legs 61 and 62, as best shown in Fig. 3, so that when the shell is secured to the cap 45 the space between the side walls 90 and the outer walls 68 and 69 of the legs 61 and 62 is greater adjacent the bottom of the cover than at the top thereof. The end portions 97 and 98 of the side walls 90 adjacent the end walls 91 are set inwardly and taper downwardly at the same angle as the outer walls 68 and 69 of the legs 62.

Mounted on the end walls 91 of the cover 46 so as to be positioned between the inner walls 82 and 83 of the legs 61 and 62 are upwardly tapered wedge members 100. The opposite side walls 101 of the wedge members are tapered to a degree to be exactly parallel with the downwardly tapered inner walls 82 and 83 of the legs 61 and 62. The end portions of the bottom wall 92 which form continuations of the end portions 97 and 98 of the side walls 90 are arcuated, as shown at 102 and 103, to form continuations of the outer tapered walls 101 of the wedge member 100. Thus, the side and bottom walls of the shell and the side walls of the wedge member 100 form a continuous W-shaped surface which, when the cover 46 is secured to the cap 45, is disposed in spaced relationship with the W-shaped surfaces 85 and 86 of the filter spreading member 48.

The preferred form of filtering means 47 consists of a sheet of filtering material, such as a comparatively heavy felt, or the like. In practice the filtering material 47 is provided in the form of a rectangular sheet positioned in the sinuous path provided by the W-shaped space 60 between the legs 61 and 62 and the cover 46. It will be seen that with the sheet of filtering material disposed as just described, the oppositely disposed marginal edges 105 and 106 respectively are confined between the W-shaped surfaces 70 85 and 86 provided by the walls of the legs 61 and 62 and the W-shaped surface provided by the end portions of the cover and the wedge 101. The remaining oppositely disposed marginal edges 107 and 108 of the sheet 47 are confined between the upper edges of the side walls

90 of the shell and the upper portions of the outer walls 68 and 69 of the legs 61 and 62.

Formed in both of the side walls 90 of the shell 46 is a series of perforations 110, these perforations preferably extending to points closely adjacent the end portions 97 and 98 and closely adjacent to the arcuate bottom wall of the shell and the cap 45.

The intermediate longitudinally extending flat portion 111 of the bottom wall of the shell is likewise preferably perforated, as shown at 112 in Figs. 4 and 6.

The novel outlet valve 15 of my invention comprises a plate of flexible material 115, formed of rubber, Cellophane, or the like, secured to the outer side of the front wall 116 of the mouth covering portion of the mask 12, the valve plate 115 covering an outlet opening 117, and being outwardly movable by the exhalation of air by the wearer of the mask. In the preferred form shown, the valve plate 115 is positioned in an outwardly facing depression 118 formed in the wall 116, the depression 118 being deeper at the lower portion thereof than at the upper portion and extending substantially across the entire front wall 116, as shown at 120 in Figs. 1 and 4. A plurality of the openings 117 is preferably provided in that portion of the wall 116 which forms the rear wall of the depression 118, as shown in Fig. 5. The valve plate 115 is secured to the wall 116 above the outlet openings 117, by suitable means such as a rivet or an integrally formed button 121 adapted to be pressed through a hole 122 in the wall 116.

Detachably secured to the mask 12 is a guard strip 123 which extends entirely over the valve plate 115 in spaced relationship therewith to allow outward movement thereof. The manner of detachably securing the guard strip 123 to the mask preferably comprises a shallow recess 124 formed in the outer surface of the mask 12 on each side thereof, the recesses being disposed parallel with the portions of the front wall 116 on opposite sides of the depression 118. The guard strip is provided with a pair of rearwardly extending fingers 125 disposed on opposite ends of the strip, the fingers having beads 126 formed thereon adapted to snap into the recesses 124. In this preferred form, it will be seen that the upper edge of the guard strip 123 is disposed closely adjacent the upper edge of the valve plate 115 and the lower edge thereof is relatively spaced therefrom due to the slope of the wall 116 forming the rear wall of the depression 118. This permits the lower side of the valve plate 115 to swing outwardly, as indicated by dotted lines to uncover the outlets 117. If desired, the spaced relationship of the upper end of the guard strip 123 and the rear wall of the depression 118 may be arranged so that the upper edge of the valve plate 115 is pressurally retained therebetween to assist in securing the valve plate in operative position.

In the use of the respirator with the parts assembled as heretofore described, the mask is placed on the wearer's face, as indicated by the dotted outline in Fig. 3, and the head strap 40 adjusted to hold the mask tightly against the wearer's face. As before explained, the inner surface 31 of the face mold is shaped to conform to the facial contour of the wearer and as the mask is drawn tightly against the face by the head strap, the material of the face mold is capable of being deformed in a direction normal to the contacting surface to compensate for 70 75

any irregularities in the features of the wearer, and although the face-engaging surface is pre-formed, the compression of the body of the material allows it to adapt itself to conform to the 5 contour of the face, thus providing an efficient air-excluding seal between the face-engaging surface 31 of the mold and the wearer's face. This compression of the material of the mold, as distinguished from the face-engaging cushions of 10 the prior art which depend upon elasticity of the material to adapt the cushions to various facial contours, provides a more efficient seal for all 15 types of faces and is much more comfortable for the wearer. The hook portions 23 may be bent laterally toward or away from each other, effecting a decrease or increase in the width of the nose bridging portion 34 to adapt the mold to various nose contours.

The shape of the mask 12 having the nose 20 covering portion conforming generally to the contour of the wearer's nose and extending only slightly above the nostrils of the wearer so that the forward nose-engaging portion of the face mold extends only over the lower portion of the 25 nose, permits the wearer to have a normal unobstructed vision, not only straight ahead but also at a sharply downward angle, as indicated by the dotted line 130 of Fig. 3. Likewise, this feature permits the wearer to continue to wear 30 spectacles which may be necessary to his vision, or permits the use of protective goggles which are essential in various kinds of factory and mine work without interference with the efficiency of the mask and without discomfort to the wearer.

35 With the respirator in position, air is drawn into the mask by inhalations of the wearer through the perforations 110 and 112 and is forced to flow through the sheet of filtering material 47 before entering the interior of the mask. 40 The air is thus purified and cleaned of smoke, dust particles, or the like, before being breathed by the wearer. It will be seen that the manner in which the filter spreading member holds the sheet of filtering material provides four surfaces 45 of the filtering material exposed to direct contact with the air flowing through the perforations, each of the surfaces being substantially equal in area to the greatest cross-sectional area of the cover. Likewise, the space between the 50 side walls 90 of the cover and the adjacent surface of the sheet of filtering material is an important feature in that the air flowing through the perforations is not forced to flow directly through the filtering material but may circulate 55 after passing through the perforations so that the entire surface of the filtering material adjacent the perforations is effective to filter and purify the air. Thus, a thicker, finer mesh filter fabric may be employed without increasing the 60 breathing effort of the wearer to a noticeable degree. This results in a more efficient filtering action, an easier inhalation by the wearer, and an economy in the utilization of the filtering material.

65 When it is desired to change the filtering material, it is merely necessary to press the latch members 94 and to withdraw the cover, whereupon a fresh sheet of filtering material may be disposed around the surfaces 85 and 86 of the 70 legs 61 and 62 and the cover repositioned. The pressure engagement of the marginal edges of the filter sheet between the W-shaped surfaces 85 and 86 of the filter spreader and the W-shaped surfaces formed by the end portions 98 of the 75 side walls 90, the bottom wall 92 and the side

walls 101 of the wedge 100, serves to effectively prevent any air from flowing around the marginal edges of the filter sheet.

When air is expelled from the lungs of the wearer, the lower edge of the outlet valve 115 is forced from contact with the wall 116 uncovering the opening to allow the escape of exhaled air and upon subsequent inhalation by the wearer is caused to engage the wall 116 in sealing engagement therewith, effectively preventing entrance of unpurified air through the opening 117. The valve plate 115 is preferably extremely flexible, being formed of comparatively thin soft rubber, Cellophane, or the like, so that undue pressure is not required to force the valve outwardly and normal inhalations of air by the wearer effectively serve to draw the valve plate tightly against the wall 116.

The guard strip 123 serves both to limit the outward movement of the valve plate 115 and to 20 protect the material of the valve during use from sprayed materials or solids in the air which would otherwise destroy its flexibility and usefulness. The guard strip is easily detached for replacement or adjustment of the valve plate.

25 Although I have disclosed and described only one complete embodiment of my invention, it should be understood that various structural features thereof might be changed, and various modifications of the inventive combination might 30 be devised by those skilled in the art without departing from the invention the scope of which should be interpreted by the appended claims.

I claim as my invention:

1. In a respirator of the character described, 35 the combination of: a mask having a rim adapted to extend around the mouth and nostrils of a wearer and having a nostril covering portion conforming substantially to the shape of the lower portion of the nose and extending less 40 forwardly of the nose than the line of vision of the wearer; an air filtering inlet in said mask; a valved outlet in said mask; a pair of forwardly projecting hook portions formed on said rim adjacent said nostril covering portion; and a 45 face mold formed of compressible material and providing a face-engaging surface conforming generally to the facial contour of said wearer, said mold having walls forming a groove for receiving said rim and pockets in said groove engaging said hook portions for retaining said mold on said rim, said material of said mold being deformable normal to said face-engaging surface whereby an air-excluding seal is formed 50 between said face-engaging surface and the 55 wearer's face.

2. In a respirator of the character described, 60 of combination of: a mask having a rim adapted to extend around the mouth and nostrils of a wearer and having a nostril covering portion conforming substantially to the shape of the lower portion of the nose and extending only 65 slightly beyond the nose so that normal vision is not obstructed; an air filtering inlet in said mask; a valved outlet in said mask; a pair of 70 forwardly projecting hook portions formed on said rim adjacent said nostril covering portion; and a face mold formed of compressible material and comprising a continuous strip, one edge of which is adapted to be stretched around and extend over said rim, said strip having walls forming pockets engaging said hook portions for retaining said mold on said rim, and the thickness of said strip being inwardly increased in 75 portions and decreased in other portions so that 75

the inner surface thereof conforms substantially to the contours of the chin, cheeks, and nose of said wearer, said material of said strip being deformable normal to said surface when pressed against the face whereby an air-excluding seal is formed between said surface and said wearer's face.

3. In a respirator of the character described, the combination of: a mask adapted to cover the mouth and nostrils of a wearer and comprising a rigid shell having secured thereto a face mold formed of compressible material conforming substantially to the facial contour of said wearer; a valved outlet in said mask; walls forming an inlet opening in said mask; filter means comprising a cap secured to said mask and communicating with said inlet, a perforated cover having releasable latch means securing said cover to said cap, a sheet of filtering material, and an inner filter spreading member formed to hold said filtering material in a position exposing a greater area thereof to direct surface contact with air entering said perforations than the combined area of said perforations.

4. In a respirator of the character described, the combination of: a mask adapted to cover the mouth and nostrils of a wearer and comprising a rigid shell having secured thereto a face mold formed of compressible material conforming substantially to the facial contour of said wearer; a valved outlet in said mask; walls forming an inlet opening in said mask; and a filter means comprising a cap secured to said shell and communicating therewith through said opening, a perforated cover detachably secured to said cap, a sheet of filtering material, and a filter spreading member supported by said cap adapted to hold said filtering material in a position exposing a plurality of spaced faces thereof to direct surface contact with air entering said perforations and each of said faces having an area substantially equal to the greatest cross-sectional area of said cover.

5. In a respirator, the combination of: a mask adapted for air-excluding contact with a wearer's face to cover the mouth and nostrils, said mask having a suitable air outlet and an air inlet; and a filter means comprising a cap secured to said mask to communicate with said air inlet, a perforated cover detachably secured to said cap, a sheet of filtering material, and an inner filter spreading member supported by said cap and formed to hold said sheet in a position exposing a plurality of spaced faces thereof to direct surface contact with air entering said perforations and each of said faces having an area substantially equal to the greatest cross-sectional area of said cover, said cover and said filter spreading member having opposed surfaces gripping the entire marginal edge of said sheet of filtering material in sealing engagement therewith.

6. In a respirator of the character described, the combination of: a mask adapted for air-excluding contact with a wearer's face to cover the mouth and nostrils, said mask having a suitable air filtering inlet; walls forming an air outlet opening in said mask; a flap valve comprising a strip of flexible rubber secured to the outer surface of said mask and having a portion covering said opening; and a guard strip detachably secured to said mask and covering said strip in spaced relation therewith to allow outward movement of said flexible strip, the upper

edge of said strip of flexible rubber being disposed between and in clamped relationship with both the upper edge of said guard strip and the outer surface of said mask.

7. In a respirator of the character described, the combination of: a mask adapted for air-excluding contact with a wearer's face to cover the mouth and nostrils, said mask having a suitable air filtering inlet, the front wall of said mask being formed with a rearwardly extending recess having generally vertical re-entrant end walls, a re-entrant rear wall connecting said end walls and inclined rearwardly and inwardly from the top of said recess, a reentrant bottom wall connecting said end walls and extending from the lower edge of said rear wall to the front lower edge of said recess, said rear wall having formed therein an air outlet opening; a thin flexible rubber flap valve secured at its upper edge in said recess across the outside of said opening and with its lower portion free to move outwardly from said opening; and a guard strip detachably secured to said mask across said recess and substantially in the plane of the outer edges of said re-entrant end, rear and bottom walls and adapted to protect and serve as a limiting stop to said valve, said guard strip having its lower edge spaced above the forward edge of said re-entrant bottom wall.

8. In a respirator of the character described, the combination of: a mask having a rim adapted to extend around the mouth and nostrils of a wearer and having a nostril covering portion conforming substantially to the shape of the lower portion of the nose and extending only slightly beyond the nose so that normal vision is not obstructed; a pair of forwardly projecting hook portions formed on said rim adjacent said nostril covering portion; a face mold formed of compressible material and providing a face-engaging surface conforming generally to the facial contour of said wearer, said mold having walls forming a groove for receiving said rim and pockets in said groove engaging said hook portions for retaining said mold on said rim, said material of said mold being deformable normal to said face-engaging surface whereby an air-excluding seal is formed between said face-engaging surface and said wearer's face; a valved outlet in said mask; walls forming an air inlet in said mask; and a filter means comprising a cap secured to said mask to communicate with said air inlet, a perforated cover detachably secured to said cap, a sheet of filtering material, and an inner filter spreading member supported by said cap and formed to hold said sheet in a position exposing four spaced faces thereof to direct surface contact with air entering said perforations and each of said faces having an area substantially equal to the greatest cross-sectional area of said cover, said cover and said filter spreading member having opposed surfaces gripping the entire marginal edge of said sheet of filtering material in sealing engagement therewith.

9. In a respirator of the character described, the combination of: a mask having a rim adapted to extend around the mouth and nostrils of a wearer and having a nostril covering portion conforming substantially to the shape of the lower portion of the nose and extending only slightly beyond the nose so that normal vision is not obstructed; a pair of forwardly projecting hook portions formed on said rim adjacent said nostril covering portion; a face mold

formed of compressible material and providing a face-engaging surface conforming generally to the facial contour of said wearer, said mold having walls forming a groove for receiving said 5 rim and pockets in said groove engaging said hook portions for retaining said mold on said rim, said material of said mold being deformable normal to said face-engaging surface whereby an air-excluding seal is formed between 10 said face-engaging surface and said wearer's face; an air filtering inlet in said mask; walls forming an air outlet opening in said mask; a valve comprising a flexible plate secured to the outer surface of said mask and having a portion 15 covering said opening; and a guard strip detachably secured to said mask and covering said plate in spaced relation therewith to allow outward movement of said flexible plate.

10. In a respirator of the character described, 20 the combination of: a mask having a rim adapted to cover the mouth and nostrils of a wearer; said mask having an air filtering inlet and a suitable valved outlet; and a face mold secured to said rim, the material of which between its 25 inner and outer edges is out of contact with the face of the wearer and is of a flexible character to permit bodily movement of its outer portions, said face mold having a relatively thin stretchable and flexible front portion to fit over the 30 nose of the wearer and being formed at two portions of its outer face-engaging edge with thickened marginal solid enlargements having the qualities of sponge rubber, said enlargements being adapted to fit within the lateral nose 35 hollows of the wearer, said mold being also formed with a continuous face engaging bead of lesser cross-sectional size than said enlargements and extending from one of said enlargements to the other, said bead being adapted to 40 fit the cheeks and undersurface of the chin of the wearer, said enlargements and bead being capable of being compressed normally of the plane of the adjacent portions of the mold upon contact with the face of the wearer.

45. 11. In a respirator of the character described, the combination of: a mask having a rim adapted to extend around the mouth and nostrils of a wearer and having a nostril covering portion conforming substantially to the shape of the 50 lower portion of the nose; an air filtering inlet in said mask, a valved outlet in said mask; a pair of forwardly projecting hook portions formed on said rim adjacent said nostril covering portion and adjacent the sides of the bridge 55 of the nose of the wearer, said hook portions being adapted to be bent toward or from each other to adapt the mask to various nose contours; and a face mold formed of flexible material secured to said rim and hook portions in air-excluding relationship therewith and adapted to conform to the face of the wearer in air-excluding relationship therewith.

60. 12. In a respirator of the character described, the combination of: a mask adapted for air-excluding contact with a wearer's face, provided with a valved outlet and having a bottom wall; a filter element in sheet form; a form for said

filter element shaped to receive the sheet on its external surfaces in convoluted form, said sheet being unsupported vertically by said form; a detachable cover for said filter element provided with contact surfaces adapted to mate with said external surfaces on the filter form and grip and vertically support the filter element therebetween when said cover is in closed position; and means independent of said cover for securing said form to said bottom wall in rigid relation thereto.

13. In a respirator of the character described, the combination of: a mask adapted to cover the mouth and nostrils of the wearer, comprising a rigid shell and a face mold secured thereto formed of flexible material adapted to fit the face of the wearer in air-excluding relationship therewith; a valved outlet in said mask; walls forming an inlet opening in said mask; a box-like filter shell secured to said mask, said filter shell being formed with two perforated side walls and a perforated bottom wall; a filter element; and a frame for said element mounted within the shell and formed to hold the filter element with two first portions substantially parallel to 25 and normally spaced from and within said side walls, and with at least two other portions between said first two portions and separated from each other to afford a chamber therebetween in communication with the perforations in said bottom wall of said shell.

14. In a respirator of the character described, the combination of: a mask having a rim adapted to extend around the mouth and nostrils of a wearer and (having a portion covering the 35 lower portion of the nose); an air filtering inlet in said mask; a valved outlet in said mask; a pair of hook portions projecting forwardly of the face of the wearer formed on said rim adjacent said nose covering portion and adjacent 40 the sides of the bridge of the nose of the wearer, said hook portions being adapted to be bent toward or from each other to adapt the mask to various nose contours; and a face mold formed of flexible material secured to said rim and hook portions in air-excluding relationship therewith and adapted to conform to the face of the wearer in air-excluding relationship therewith.

15. In a respirator of the character described, the combination of: a mask having a rim adapted to extend around the mouth and nostrils of a wearer and having a portion covering the lower portion of the nose; an air filtering inlet in said mask; a valved outlet in said mask; a pair of hook portions projecting forwardly of the face 55 of the wearer formed at symmetrically related points on the two sides of said rim respectively, said hook portions being adapted to be bent toward or from each other to adapt the mask to various facial contours; and a face mold formed of flexible material secured to said rim and hook portions in air-excluding relationship therewith and adapted to conform to the face of the wearer in air-excluding relationship therewith.

HOWARD B. LEWIS.

CERTIFICATE OF CORRECTION.

Patent No. 2,220,374.

November 5, 1940.

HOWARD B. LEWIS.

It is hereby certified that error appears in the printed specification of the above numbered patent requiring correction as follows: Page 4, second column, line 60, claim 2, for the word "wear" read --wearer--; page 6, first column, line 21, claim 10, strike out the semicolon and insert instead a comma; line 37, same claim, after "cross-sectional" strike out the hyphen; same page, second column, lines 35 and 36, claim 14, strike out the parenthesis marks before "having" and after "nose"; and that the said Letters Patent should be read with this correction therein that the same may conform to the record of the case in the Patent Office.

Signed and sealed this 17th day of December, A. D. 1940.

(Seal)

Henry Van Arsdale,
Acting Commissioner of Patents.
